UNITED STATES PATENT OFFICE

160,343

WOMAN'S STOCKING OR SIMILAR ARTICLE

Rolf P. Scherzer, Hatboro, Pa.

Application June 23, 1950, Serial No. 10,698

Term of patent 14 years

(Cl. D47—7)

To all whom it may concern:

Be it known that I, Rolf P. Scherzer, a citizen of the United States, residing at Hatboro, in the county of Montgomery and State of Pennsylvania, have invented a new, original, and ornamental Design for a Woman's Stocking or Similar Article, of which the following is a specification, reference being had to the accompanying drawing, forming part hereof, in which:

I claim:

The ornamental design for a woman's stocking or similar article, as shown.

ROLF P. SCHERZER.
